UNITED STATES PATENT OFFICE.

WILLIAM R. MACKLIND, OF CLEVELAND, OHIO.

SUBMARINE BOAT.

1,180,861

Specification of Letters Patent. Patented Apr. 25, 1916.

Application filed April 20, 1915. Serial No. 22,708.

To all whom it may concern:

Be it known that I, WILLIAM R. MACKLIND, a citizen of the United States, residing at Cleveland, in the county of Cuyahoga and State of Ohio, have invented certain new and useful Improvements in Submarine Boats, of which the following is a specification.

My invention relates to improvements in submarine boats, the primary object being to provide a generally improved submarine boat particularly designed and adapted to provide great hull strength and displacement as well as one providing a maximum degree of safety, cruising range, surface and submersion speed, submerged cruising range, torpedo and crew and gun carrying capacity, seaworthiness, submersion range, endurance of submersion, available hull 20 space, defensive power, stability, and visibility of object to be attacked.

The present type or class of submarines now in use are limited in cruising range, torpedo and gun and crew carrying capacity, 25 submersion range, as well as in hull space. They are also more or less unsafe when submerged, due largely to the hulls being of the single type, and in case of a failure of the pumps or a leak developing the chance 30 of coming to the surface is limited. Furthermore, by reason of their single hull type of construction, the length and diameter is limited thereby correspondingly limiting the necessarily required or expected functions of a submarine.

In carrying out my invention I provide an improved compound or master hull of great strength and displacement made up of a plurality of self contained hulls of 40 relatively small diameter preferably surrounded by a suitable fluid such as water, or the like, or a suitable composition, such super or compound hull being particularly designed and adapted to provide great 45 serve buoyancy when submerged, carrying capacity, submersion range, safety when submerged, and ability to return to the surface when parts of the compound or master hull are filled with water.

50 A still further object of this invention is to provide ample and comfortable crew quarters, large fuel and ammunition carrying capacity, power space, seagoing ability, long cruising range, large cruising deck,

and gun carrying capacity, ample cruising 55 and long bridge visibility, duplicate wireless equipment, reserve periscopes, and ample life boat carrying capacity.

It is believed that a submarine of my improved construction or type will largely 60 overcome the present objections and weaknesses of the present class or type of submarine boats, and in addition will extend the range of submarine work far beyond that accomplished at the present time; that 65 it will be possible to go to sea for long periods, and owing to its larger gun and crew carrying capacity will become the superior of the torpedo boat and torpedo boat destroyers, such increased gun range making 70 it possible to keep the torpedo boat and torpedo boat destroyers out of range while its own guns will reach them readily.

The improved construction renders it possible to build the boat to any length desired 75 thereby increasing proportionately the carrying capacity, fighting ability, and the like.

With the above mentioned and other ends in view, the invention consists in the novel construction, arrangement, and combination 80 of parts, hereinafter described, illustrated in some of its embodiments in the accompanying drawings, and particularly pointed out in the appended claims.

Referring to the drawings forming a part 85 of this specification, Figure 1, is a top plan view of a submarine boat constructed in accordance with this invention. Fig. 2, a side elevation of the same. Fig. 3, an enlarged cross sectional view taken on lines 3—3 of 90 Fig. 1. Fig. 4, a front elevation of the same. Fig. 5, a rear elevation of the same. Fig. 6, a central longitudinal sectional view taken on line 6—6 of Fig. 1. Fig. 7, a front elevation or bow end view of a modified form 95 of same. Fig. 8, a similar view of a further modification. Fig. 9, a view of a still further modified form of same.

Similar numerals of reference designate like parts throughout all the figures of the 100 drawings.

The compound or main hull of the improved submarine comprises a plurality of relatively small self-contained longitudinally extending cylindrical hulls 1, having 105 tapered or converged ends 1^a, said cylindrical hulls 1, being suitably connected to each other by means of a connecting and support

ing structure or medium 2. The connecting and supporting structure 2, interposed between the self-contained or individual cylindrical hulls 1, is preferably provided with a plurality of longitudinally extending passages or spaces ^{2a}, which may be filled with water, or some other suitable filler such as cork, cement, diatomite, or the like. The cylindrical hulls 1, are further connected and supported by means of an outer shell or false hull 3, and a connecting or bridge structure ^{3a}. The outer shell or false hull 3, is preferably provided with a plurality of conveniently spaced water circulating ports or passages ^{3b}. The connecting and supporting structure 2, is further provided with a plurality of longitudinally extending compartments or containers 4, for receiving and containing fuel, air, or the like. As a means of establishing communication between the various cylindrical hulls 1, the connecting and supporting structure 2, is further provided at suitable intervals with a series or plurality of ports or passages ^{2b}, intersecting the hulls 1, said ports or passages ^{2b}, being adapted to be opened and closed through the medium of suitable doors ^{2c}. The cylindrical hulls 1, are further provided with suitable bulk-heads ^{1b}, dividing the same into suitable compartments ^{1c}, said bulk-heads being provided with suitable doors ^{1d}. The conning tower 5, is provided with a deck entrance or port ^{5a}, which may be opened and closed through the medium of a suitable door ^{5b}. The connecting or bridge structure ^{3a}, is provided with a suitable cruising deck 6, and the cruising deck may be provided at suitable intervals with suitable working deck entrances or ports ^{6c}, and with suitable hull ventilator tubes ^{6a}, such ventilator tubes also forming emergency exits leading from the cylindrical hulls 1, to the cruising deck 6. The improved submarine may be provided at its ends with suitable torpedo tubes 7, and the conning tower 5, is provided with suitable conning tower periscopes ^{5c}, the latter being adapted to be controlled by means of suitable periscope valves ^{5d}, operable from within the dome portion of the conning tower. The improved submarine may also be provided with a suitable cruising bridge 8, and cruising deck periscopes ^{6b}, as well as suitable wireless apparatus 9. The cruising deck 6, may also be provided with suitably mounted fluid or water tight gun cases 10, adapted to receive and contain suitably mounted guns or projectile throwing means ^{10a}. The propellers 11, and rudders 12, may be of any suitable and convenient form or type and may be operated through any suitable and convenient power and mechanism and which for the purpose of this application

need not be further described in detail. So likewise as to the pumping mechanism and submersion and raising means which are well known to those skilled in the art to which this invention relates.

The connecting and supporting or tie structure 2, for connecting and supporting the cylindrical self-contained hulls 1, may be varied according to the structural advantages to be obtained, and it will be apparent in view of the nature of this invention that the drawings are necessarily diagrammatic in their nature.

The modifications shown in Figs. 7, 8 and 9 will be readily understood in view of the foregoing description, and are merely suggestive of the many forms which my invention may take.

From the foregoing description, taken in connection with the accompanying drawings, the operation and advantages of my invention will be readily understood.

Having thus described some of the embodiments of my invention, without having attempted to set forth all the forms in which it may be made or all the modes of its use, what I claim and desire to secure by Letters Patent, is,—

1. A submarine, comprising a plurality of individual hulls.
2. A submarine, comprising a compound or main hull made up of a plurality of individual longitudinally extending hulls and means for structurally connecting said hulls.
3. A submarine, comprising a compound hull made up of a plurality of longitudinally extending self-contained hulls having transverse intercommunicating passages.
4. A submarine, comprising a plurality of self-contained hulls, and a supporting structure interposed between and connected to said hulls.
5. A submarine, comprising a plurality of self-contained hulls structurally connected and provided with a cruising deck, and a cruising bridge above said deck.
6. In a submarine, a plurality of hulls having bulk-heads and provided with an interposed supporting structure having transversely extending communicating passages, and means for opening and closing said passages.
7. A submarine, comprising a plurality of longitudinally extending hulls connected by means of an interposed supporting structure, an outer or false hull, and a superposed bridge structure.
8. A submarine, comprising a plurality of hulls provided with bulk-heads, a supporting structure interposed between and connected to said hulls and provided with longitudinally and transversely extending passages, said transversely extending passages communicating with said hulls.
9. A submarine, comprising a plurality of

hulls having their opposite ends tapered, means for connecting said hulls together including an outer or false hull and a superposed bridge structure, and containers arranged within said hull connecting means.

10. In a submarine, a plurality of hulls having transversely extending passages, a supporting structure interposed between said hulls and provided with longitudinally extending passages, a plurality of storage tubes arranged in said supporting structure, and a superposed bridge structure provided with a cruising deck!

15. 11. In a submarine, a compound hull made up of communicating longitudinally extending self-contained hulls, means for throwing said hull into and out of communication with each other, and means for propelling, submerging and raising said compound hull.

12. In a submarine, a plurality of self-contained hulls united to each other by means of an interposed supporting structure and a superposed bridge structure, a cruising deck on said bridge structure, a conning tower, and an elevated cruising bridge above said cruising deck.

13. A submarine, comprising a compound hull made up of a plurality of longitudinally extending compartments, an interposed connecting and supporting structure provided with transversely extending ports or passages communicating with said compartments, and a plurality of longitudinally extending compartments or containers in said interposed connecting and supporting structure.

14. A submarine, comprising a compound hull made up of longitudinally extending cylindrical shaped compartments, a supporting structure interposed between and connected to said compartments and provided with longitudinally and transversely extending passages, said transversely extending passages communicating with said compartments, and longitudinally extending compartments or containers arranged within said supporting structure.

50. 15. In a submarine, a plurality of structurally connected communicating hulls divided into compartments, a bridge structure provided with a cruising deck, a conning tower provided with entrance hatches, ventilating tubes leading from said cruising deck to said hulls, and means for closing said hatches and tubes when the submarine is being submerged.

60. 16. In a submarine, the combination with a plurality of structurally connected communicating hulls provided with a cruising deck and entrance hatches and ventilator tubes leading therefrom, means for closing said entrance hatches and ventilator tubes when the submarine is being submerged,

and means for independently opening and closing communication between said hulls.

17. In a submarine, a compound hull comprising longitudinally extending hulls, a supporting structure interposed between and connected to said hulls and provided with longitudinally and transversely extending passages, a bridge structure provided with a conning tower and ventilator tubes, a cruising deck on said bridge structure, and a cruising bridge above said conning tower.

18. In a submarine, a compound hull provided with longitudinally extending communicating compartments, a supporting and connecting structure provided with longitudinally and transversely extending passages, said transversely extending passages communicating with said compartments, a bridge structure provided with a deck and having hull ventilator and emergency exit tubes, a conning tower provided with valved periscopes and communicating with one of said longitudinally extending compartments, and a cruising bridge carried by said deck above said conning tower.

19. In a submarine, a compound hull made up of a plurality of connected communicating longitudinally extending hulls provided with bulk-heads, an outer or false hull, a plurality of storage compartments or containers interposed between said longitudinally extending hulls, a superposed bridge structure, a conning tower, an entrance hatch leading from said conning tower to some of said hulls, hull ventilator or exit tubes leading from some of the other of said hulls, means for automatically closing the entrance hatches and ventilator tubes when the submarine is being submerged.

20. In a submarine, a plurality of self-contained hulls united to each other by means of an interposed supporting structure and a superposed bridge structure.

21. In a submarine, a compound hull made up of a plurality of hulls and an interposed connecting and supporting structure of open formation.

22. In a submarine, a plurality of hulls united to each other by means of an interposed open supporting structure, a false hull, and a superposed bridge structure.

23. In a submarine, a compound hull comprising longitudinally extending self-contained hulls, a connecting and supporting structure interposed therebetween, and a superposed bridge structure and cruising deck.

24. In a submarine, a compound hull comprising a plurality of hulls, a supporting structure of open formation interposed therebetween, and an outer open false hull.

25. In a submarine, a plurality of hulls united to each other by means of an interposed connecting and supporting structure having transversely extending passages communicating with said hulls.

26. In a submarine, a compound hull made up of communicating longitudinally extending hulls and an interposed connecting and supporting structure having longitudinally extending passages between said hulls.
27. In a submarine, a plurality of self-contained hulls having transversely extending passages, a supporting structure interposed between said hulls and provided with longitudinally extending passages, and a superposed bridge structure and a cruising deck.
28. In a submarine, a compound hull made up of longitudinally extending self-contained hulls having tapered ends, a supporting structure interposed between said hulls, means for throwing said hulls into and out of communication with each other, and a superposed bridge structure.
29. A submarine, comprising a compound hull made up of longitudinally extending hulls provided with bulk-heads dividing the same into suitable compartments, a supporting structure interposed between said hulls and provided with longitudinally and
- transversely extending passages, said transversely extending passages communicating with said compartments.
30. A submarine, comprising a plurality of self-contained intercommunicating watertight hulls.
31. A submarine, comprising a plurality of hulls having tapered ends, and means including an outer or false hull for structurally connecting said hulls.
32. A submarine, comprising a compound or main hull made up of a plurality of longitudinally extending individual hulls and an outer or false hull, and a plurality of containers interposed between said individual hulls.
33. In a submarine, a compound hull made up of a plurality of longitudinally extending hulls having their opposite ends tapered and provided with torpedo tubes.

In testimony whereof I have affixed my signature in presence of two witnesses.

WILLIAM R. MACKLIND.
